(57) **CLAIM**

We claim the ornamental design for a vacuum cleaner floor tool, as shown and described.

DESCRIPTION

FIG. 1 is a front perspective view of a first embodiment of a vacuum cleaner floor tool showing the new design;

FIG. 2 is a right side view thereof.

FIG. 3 is a left side view thereof.

FIG. 4 is a top view thereof.

FIG. 5 is a bottom view thereof.

FIG. 6 is a front view thereof.

FIG. 7 is a rear view thereof.

FIG. 8 is another front perspective view thereof with environmental structure omitted.

FIG. 9 is a front perspective view of a second embodiment of a vacuum cleaner floor tool showing the new design.

FIG. 10 is a right side view thereof.

FIG. 11 is a left side view thereof.

FIG. 12 is a top view thereof.

FIG. 13 is a bottom view thereof.

FIG. 14 is a front view thereof.

FIG. 15 is a rear view thereof.

FIG. 16 is another front perspective view thereof with environmental structure omitted.

FIG. 17 a front perspective view of a third embodiment of a vacuum cleaner floor tool showing the new design.

FIG. 18 is a right side view thereof.

FIG. 19 is a left side view thereof.

FIG. 20 is a top view thereof.

FIG. 21 is a bottom view thereof.

FIG. 22 is a front view thereof.

FIG. 23 is a rear view thereof; and,

FIG. 24 is another front perspective view thereof with environmental structure omitted.

The details shown in broken lines form no part of the claimed design.
